M. MEYBERG

DISPLAY CASE

Filed Oct. 17, 1921

Inventor
Manfred Meyberg
By Lyon & Lyon Atty.

UNITED STATES PATENT OFFICE.

MANFRED MEYBERG, OF LOS ANGELES, CALIFORNIA, ASSIGNOR TO GERMAIN SEED AND PLANT COMPANY, OF LOS ANGELES, CALIFORNIA, A CORPORATION OF CALIFORNIA.

DISPLAY CASE.

Application filed October 17, 1921. Serial No. 508,114.

To all whom it may concern:

Be it known that I, MANFRED MEYBERG, a citizen of the United States, residing at Los Angeles, in the county of Los Angeles and State of California, have invented new and useful Improvements in Display Cases, of which the following is a specification.

This invention relates to cases of the character employed for holding a series of seed containing envelopes or other like parcels or packets, and an object of the invention is to provide a case that can be conveniently used for display of the contents of the case.

Another object is to make provision for folding the case so that it is in convenient form for shipping and storage.

Another object is to make provision for mounting a series of trays in such manner that they can be lowered into a receptacle and the cover of the receptacle closed, or positioned in stepped relation so that each tray and its contents is visible from the front of the device.

The accompanying drawings illustrate the invention:

Fig. 1 is a perspective view of a case embodying the invention, the parts being in the positions they occupy when the case is in use.

Fig. 2 is an end elevation of the case, portions of the box or container being broken away to disclose the parts within. The parts are in the same positions as in Fig. 1.

Fig. 3 is a transverse section of the case, with the trays in lowered position within the container.

Fig. 4 is a longitudinal section on line indicated by 4-4 Fig. 3, the parts being in the folded or closed positions.

Fig. 5 is an enlarged fragmental section on line indicated by 5-5 Fig. 2.

Fig. 6 is an enlarged fragmental plan section on line indicated by 6-6 Fig. 2.

There is provided a box or container of any suitable shape, rectangular in the instance shown and comprising end walls 7, a rear wall 8, and a front wall comprising a stationary section 9 and a movable section 10 which is hinged at 11 to the section 9. The container also comprises a bottom 12, a cover or lid 13 hinged at 14 to the back member 8, and movable flaps 15 hinged at 16 to the end members 7. The flaps 15 constitute abutments to prevent closing of the

lid 13, when said flaps are in the raised positions as in Figs. 1, 2, and 3.

The rear ends of the flaps 15 are provided with laterally extending hooks 17 adapted, when the flaps 15 and lid 13 are upright, to engage eyes 18 formed upon the inner face of the lid 13. The end portions of the hooks 17 are at right angles to the flaps 15 so that they may be readily engaged with the eyes 18 by first raising the lid 13 into the position shown in Fig. 3 and then opening out the flaps 15 so that the end portions of the hooks pass into the eyes. The hooks and eyes 17, 18 constitute one form of cooperating means detachably connecting the lid and flaps. The lid 13 is preferably provided with a flange 19 which overlaps the end walls 7 and front section 10 of the container when the lid is in the closed position shown in Fig. 4.

Within the container is mounted a series of longitudinal extending trays 20 which are channel- or trough-shaped. The trays 20 are pivoted at each end at 21 to a pair of parallel-motion bars 22, which constitute means movably connecting the trays for simultaneous operation. The pivots in each end of each tray are in vertical alinement so that the trays will not be caused to tilt when moved from their closed positions, indicated in Figure 3, to their open positions, as in Figure 2.

The foremost tray 20 is secured by any suitable means to the bottom 12 of the container, in the instance shown, the fastening means being bolts 23. The opposite ends of the rearmost tray 20 are provided with laterally extending hooks 24 adapted to catch upon the upper edges of the flaps 15 when the flaps are in the raised positions. These hooks 24 are shown thus engaged in Figs. 1 and 2 of the drawings. When the hooks 24 thus engage the flaps 15, the bars 22 will be held in the inclined positions shown clearly in Fig. 2, thus holding each successive tray, beginning with the second from the front, at a greater elevation than the next tray in front or, in other words, holding the trays in stepped relation. The trays are so spaced along the bars 22 that, when the bars are in the inclined positions shown in Fig. 2, the lower front corner of each is adjacent the upper rear corner of the tray immediately in front thereof. Thus,

when seed packets or the like are placed within the trays, the packets in any particular tray can be readily inspected without raising them as would be necessary if the 5 stepped construction were not provided.

The flaps 15, hooks 17, 24, eyes 18, and bars 22 together constitute cooperating means between the lid and the trays to hold the lid in open position and to hold the 10 trays in stepped position.

When the hooks 24 are released from the flaps 15 the trays can be dropped within the lower portion of the receptacle and, when thus positioned, the trays are separated from 15 one another by spaces 25, and rest upon the bottom of the container. The stationary section 9 is of substantially no greater height than the front tray 20; so that when the section 10 is opened, as in Figs. 1 and 2, the 20 upper portions of packets placed within said tray can be readily observed from position in front of the case.

In practice, the various movable parts of the case will be placed in the folded positions indicated in Fig. 4, when the case is to 25 be shipped or stored. This case thus folded is convenient for a wholesaler of plant seeds to distribute to the various seed retailing houses for retailing of the wholesaler's seeds. 30 When the retailer receives the case, he will raise the lid 13, open out the flaps 15 and engage the hooks 17 with the eyes 18 to hold the lid 13 against closing or opening any wider, and he will then grasp the rear- 35 most tray 20 and raise the same sufficiently high so that he may engage the hooks 24

over the upper edges of the flaps 15. He will also lower the front section 10, and the case is then in condition for exhibiting seed packets that may be placed within the trays. 40

It is to be understood that when the case is shipped the seed packets may be placed in trays and shipped with the case, so that when the case is opened by the merchant, the goods will be immediately on display. Thus 45 the case affords convenient means for wholesalers of seeds and the like placing with retailers the seed packets and a suitable holder for exhibiting them in a neat manner to the customers of the retail merchant. 50

It will be understood from the foregoing description, that the case is of very simple and durable construction, and that it may be readily opened for display of the goods. 55

I claim:

In a display case, the combination of a container having a lid, flaps hinged to the ends of the container, cooperating means between the flaps and lid engageable by outward swinging of the flaps to detachably 60 connect the lid and flaps, trays in the container, means movably connecting the trays for simultaneous operation, and cooperating means between the flaps and one of the trays to hold the flaps against inward swing- 65 ing and to support said tray.

Signed as Los Angeles, California, this 30th day of September 1921.

MANFRED MEYBERG.
